DESIGN FOR AN EYEBROW PENCIL

Henry Becker, Culver City, Calif.

Application June 25, 1948, Serial No. 147,187

Term of patent 14 years

(Cl. D86—10)

To all whom it may concern:

Be it known that I, Henry Becker, a citizen of the United States and resident of Culver City, in the county of Los Angeles and State of California, have invented a new, original, and ornamental Design for an Eyebrow Pencil, of which the following is a specification, reference being had to the accompanying drawings, forming part thereof, in which:

Fig. 1 is an elevational view of an eyebrow pencil showing my new design;

Fig. 2 is a top view thereof; and

Fig. 3 is a bottom view of my eyebrow pencil.

I claim:

The ornamental design for an eyebrow pencil, as shown.

HENRY BECKER.
